DOOR SWITCH

David Conlan, Brooklyn, N. Y., assignor to Conlan
Electric Corporation, New York, N. Y.

Application March 11, 1944, Serial No. 526,081

16 Claims. (Cl. 200—54)

The invention herein disclosed relates to door operated switches, such as used aboard ship for cutting off lights in a stateroom when a stateroom door is opened.

Special objects of the invention are to provide a switch of this character, which will be protected against injury from the slamming or hammering action of a door and which will remain in operative condition regardless of warping or sagging of the door or other changes in the door closing action.

Other objects of the invention are to provide a switch of the character outlined, of rugged, strong construction, which will not require any particular attention or servicing and which will be of simple, durable and wholly practical construction.

Other desirable objects and the novel features by which all purposes of the invention are attained are hereinafter set forth or will appear in the course of the following specification.

The drawings accompanying and forming part of the specification illustrate a present practical embodiment of the invention, but it will become apparent as the invention is understood that the structure may be modified and changed in various ways, all within the true intent and broad scope of the invention, as hereinafter defined and claimed.

Fig. 1 is a front view of the switch unit as applied to the door casing, with the cover of the box removed.

Fig. 2 is a similar view, with the wiring panel over the switch removed.

Fig. 3 is a broken view showing parts in position with the switch operating plunger forced in by the door.

Fig. 4 is a like view but showing the locking sleeve turned to secure the plunger in retracted position.

Figs. 5 and 6 are horizontal sectional views as on the lines 5—5 and 6—6 respectively of Figs. 3 and 4.

Fig. 7 is an enlarged broken sectional detail of the door plunger structure with the parts in the position shown in Fig. 3.

Fig. 8 is a part vertical sectional view of the structure shown in Fig. 1.

Figs. 9 and 10 are enlarged cross-sectional details as on lines 9—9 and 10—10 respectively of Fig. 3.

Figs. 11 and 12 are cross-sectional details as on substantially the lines 11—11, 12—12 of Fig. 4.

Fig. 13 is an end view and Fig. 14 is a longi-

tudinal sectional view of the guiding and packing tube for the spring abutment plunger.

Figs. 15 and 16 are detached views of the inner, plunger guiding and supporting tube and the outer, locking sleeve for the plunger.

Fig. 17 is a front view of the switch, with terminal block removed, in the closed circuit position and with the locking sleeve turned as in Fig. 4, to secure it in that relation.

Fig. 18 is a similar view, with a special terminal block in place and with the door plunger unlocked and projecting as in the switch open position of Fig. 2.

Fig. 19 is a broken sectional view of a modified form of the plunger construction.

The complete switch unit comprises a watertight enclosure adapted for mounting on a door casing and containing switch mechanism operable by a projecting door engageable plunger.

The enclosure is shown as consisting of a box 20, having a watertight cover 21.

The switch mechanism may vary in construction, the one shown being of the snap action spring toggle type having a movable contact 22, adapted to be snapped into and out of engagement with the stationary contacts 23, through the controlling agency of a plunger 24, mounted for sliding movement in a bracket 25. The contacts 23, have suitable wiring terminals 26, 27.

The door actuated plunger is designated 28, and is shown guided in a cross tube 29, welded or otherwise fixedly secured in opposite side walls of the box.

The plunger 28, at its inner end carries a laterally projecting lug 30, having an inclined cam face 31, at its inner end for depressing the switch plunger and a straight continuation or land 32, for holding the switch plunger in the depressed, switch closed position.

To reduce friction and promote smoother, easy switch action, the plunger or cam face may carry a friction eliminating roll, such as indicated at 33.

The box wall through which the door plunger projects is shown as carrying an internal tubular projection 34, with screw discs 35, 36, therein, for compressing suitable packing 37, therebetween, into water sealing engagement with the plunger.

The plunger guiding tube 29, is shown as longitudinally slotted at 38, for projection and guiding of the switch operating lug, the closed end of this slot at 39, limiting the out-stroke or extent of projection of the plunger.

In the illustration, the slot 38, is shown as opening out through the opposite end of the

guide tube in line with the radially extending portion 40, of a keyhole slot formed in a flange 41, in a packing tube 42, fixed in the wall of the box. The circular portion 43, of this keyhole slot is of a size to receive and guide the inner end of a spring abutment plunger 44. The latter carries a laterally extending lug 45, adapted to be entered through the notch 40, and to extend radially out through the slot 38, into a keyway in a locking sleeve surrounding the guide tube.

A coil spring 46, interposed in the guide tube between the two plungers serves to yieldingly project the door plunger and to retain the abutment plunger in either one of two fixed positions.

The abutment plunger is shown as packed watertight by packing 47, clamped between the discs 48, 49, screwed into the tube or bushing 42, these having cross slots 50, or the like, engageable by a suitable wrench for securing them in place. The inner screw disc 48, by closing the radial notch 40, behind the lug 45, serves as a retainer to hold the spring abutment plunger in guided position within this watertight bushing.

The locking sleeve 51, is shown as rotatably engaged about the guide tube and as longitudinally slotted at 52, for passage of the cam lug 30, at one end and to receive the key lug 45, of the spring abutment plunger at the opposite end. This slot is shown as widened at 53, to provide an abrupt locking shoulder 54, which when the door plunger is pushed in, can be turned in front of the cam 30, to lock the plunger in the retracted position, Fig. 4.

To permit the rotative adjustment of the key lug 45, necessary to turn the sleeve into the locking position, the open end of the guide slot 38, in the inner tube is shown as widened out at 55, Figs. 7 and 15.

The locking sleeve while freely rotatable is held against longitudinal shifting movement by being confined at one end, Fig. 7, by the inner end of the packing tube 34, and at the opposite end by the annular flange 41, in the other packing tube 42.

In the unlocked position of the parts, Figs. 3, 5 and 7, the locking sleeve is secured by reason of the lug 45, on the spring abutment plunger 44, seating in the notch 40, in flange 41, at the back. To release the plunger and locking sleeve, the plunger may be pushed inward to the dotted line position shown in Fig. 7, clear of the notch 40, and then the plunger may be turned in the wider portion 55, of the slot in the guide tube, so as, by engagement in slot 52, in the sleeve, to rotate the sleeve into position to carry the locking shoulder 54, in front of the cam on the door plunger.

The parts are secured in this locked position, in the present illustration, by the key lug 45, of the abutment plunger dropping back into a notch or recess 56, in the face of the flange 41.

For the purpose of sliding and rotating the spring abutment plunger 44, into and out of the two positions described, this plunger may have a knob or some other suitable actuating means on the outer end of the same, such as in the illustration, a cross slot 57, for a screw driver or like tool.

The switch is shown as reinforced by a back plate 58, through which the screws 59, are extended to secure the switch structure to the back or bottom wall of the box. The switch mounting and reinforcing plate 58, is shown as

extended at 60, across the back of the switch and brought up at 61, around the end of the bracket 25, in which the plunger 24, operates, thus to reinforce the bracket and serve additionally as a guide for the switch plunger.

The switch is covered and protected in the illustration, by an overlying terminal base or panel 62, secured at one end by screws 63, engaging screw seats 64, in the insulating switch base 65, and at the other end by a screw 66, engaged with the overturned end 67, of the switch mounting plate 58.

The insulating block or panel 62, as shown in Fig. 1, covers the switch mechanism and all or the main portions of the door plunger, switch throwing cam and the guide tube and locking sleeve. This, as further shown in Fig. 8, leaves the entire forward or outer portion of the box free and clear for wiring purposes. The two usual wiring terminals 26, 27, of the switch are indicated in Figs. 1 and 8, as projecting forwardly through openings 72, in the panel, to enable direct attachment of the wire terminals 68, 69, thereto. If other wiring terminals are desirable, these may be mounted on the panel 62, after the manner indicated at 70 and 71 in Fig. 1, those at one side, if desired, being connected by a jumper or bus bar with one of the live terminals 26, 27, and those at the other side 30 being similarly connected with the other live terminal.

The cam 30, is designed to actuate the switch plunger smoothly and easily with either quick or slow door closing movements. Any extra travel, which might be occasioned by hard slamming of the door is taken up by the flat part of the cam 32, riding under the roller 33, on the end of the switch plunger, so that any overthrow which might be occasioned by door slamming or by sagging or warping of the door will not injure the switch and the switch in all cases will be properly operated and held in closed position while the door is closed.

The spring abutment plunger 44, by projection of the key lug 45, through the widened portion 55, of the slot in the inner guide tube, into the key slot 52, in the outer locking sleeve 51, serves to position and hold the locking sleeve rotatively on the guide tube. Normally the key lug 45, by its partial seating in the notch 40, Fig. 7, serves to retain the locking sleeve in the unlocked position, with the cam plunger projecting but free to be pushed inward by the door.

When it is desired to lock the switch in closed position, it is only necessary to force the door plunger inward, if it is not then held inward by the door, and then with a screw driver or other implement, push the spring plunger 44, inward far enough to carry the key lug 45, clear of the notch 40, and whereupon it can then be turned far enough to carry the locking shoulder 54, on the sleeve into position in front of the abrupt end of the cam, Figs. 4 and 6, and at which time, with inward pressure on the plunger released, the plunger will drop back to seat the key lug in the second locking notch 56. In Figs. 3 and 5, plunger 44, is shown as pushed inward for the purpose of clearing the key lug 45, from the locking notch 40, preparatory to turning it to the Figs. 4 and 6 position for rotating the sleeve into locking position.

To prevent the spring abutment plunger being pushed inward too far, that is, to a point where the key lug 45, might enter the narrow guide slot 38, and thus hold the plunger against rotary

adjustment, some kind of stop may be provided, such as a cross pin 73, in the outer end portion of the plunger, which will engage the end of the packing tube 42, to limit the plunger to a position where the key lug 45, may operate only in the wider portion 55, of the slot in the guide tube.

Figs. 17 and 18 show the switch as equipped with a special wiring panel 62, carrying a terminal block 74, removably secured on the panel by screw 75. This terminal block may be of any desired size and carry any number of wiring terminals 76. Those two nearest the center of the block are shown as equipped with binding screws 77, for securing the wires 78, 79, brought up from the switch terminals (26, 27) at the back of the panel.

The box in this particular illustration is shown as having conduit fittings 80, at both the top and the bottom, provided for carrying continuous wiring through the box, in the clear portion in front of the terminal block.

Special means may be provided for accurately locating the switch mechanism in the box, so that it will always be properly operated by the cam on the plunger. Such means are shown at 81, Figs. 17 and 18, in the form of guide pins projecting from the back of the box into correspondingly disposed positioning openings in the switch base plate 58. These guide pins take some of the load off the securing screws 59, and are particularly desirable in the case of heavier operating switch mechanism, such as may be present in the case of double poled or "quad" switches used in the box.

The form of the invention illustrated in Fig. 19, is in some respects simpler and less expensive in construction than that first disclosed, particularly in that the guide tube and locking sleeve are dispensed with and the two plungers are connected so as to operate as one, through the packing tubes in the opposite sides of the box.

Specifically, the door engaged plunger 28', is shown as screwed into one end of a cylindrical cam member 30', and the abutment plunger 44', is shown screwed in the opposite end of the same cam member and these two plungers operating through packing glands 34', 42', in the opposite box walls. The spring 46', in this case, is interposed between the inner end of packing tube 42', and the inclined or conical end portion 31', of the cam and the opposite end of the cam is shown as engageable with the inner end of packing tube 34', to limit the outward thrust of the door plunger.

In this last illustrated form of the invention, the locking of the switch in closed condition is accomplished by pulling on the knob 82, on the outer end of abutment plunger 44', to clear the cross pin 83, on that plunger from slot 34, in the guide tube 42', and by then turning the knob and dropping it back to engage this cross pin in a holding or locking notch 85, and in which latter relation, the connected plungers and cam will be held retracted, with the switch in closed condition.

What is claimed is:

1. A door switch, comprising an enclosure for mounting on a door casing, a plunger projecting from said enclosure for actuation by a door in said door casing, an electric switch mounted in said enclosure and having a switch operating element, a cam on said plunger within the casing and operatively engaged with said switch operat-

ing element, a tubular member about said plunger, said tubular member and plunger being relatively rotatable in the retracted position of the plunger and having shoulders co-operatively engageable upon such relative rotation in the retracted position to secure and hold said plunger so retracted.

2. A door switch, comprising an enclosure for mounting on a door casing, a plunger projecting from said enclosure for actuation by a door in said door casing, an electric switch mounted in said enclosure and having a switch operating element, a cam on said plunger within the casing and operatively engaged with said switch operating element, a locking sleeve adjustable about said plunger within the enclosure and having a holding shoulder for engagement with the cam and externally accessible means for effecting locking and unlocking adjustments of said sleeve.

3. A door switch, comprising a box for mounting on a door casing, a guide tube extending across between opposite side walls of said box, a door engageable plunger projecting from one end of said tube, a spring abutment engaged in the opposite end of the tube, a plunger projecting spring engaged in the tube between said abutment and plunger and an electric switch within the box having a movable element operatively connected with said plunger.

30 4. A door switch, comprising a box for mounting on a door casing, a guide tube extending across between opposite side walls of said box, a door engageable plunger projecting from one end of said tube, a spring abutment engaged in the opposite end of the tube, a plunger projecting spring engaged in the tube between said abutment and plunger, an electric switch within the box, said switch having a movable operating element and said plunger having a projecting portion operatively engaging said element, the tube having a slot through which said projecting portion protrudes.

45 5. A door switch, comprising a box for mounting on a door casing, a guide tube extending across between opposite side walls of said box, a door engageable plunger projecting from one end of said tube, a spring abutment engaged in the opposite end of the tube, a plunger projecting spring engaged in the tube between said abutment and plunger, an electric switch within the box, said switch having a movable operating element, said plunger having a projecting portion operatively engaging said element, the tube having a slot through which said projecting portion protrudes and a locking member movably mounted on said tube and having a locking shoulder cooperative with said projecting portion of the plunger.

50 6. A door switch, comprising a box for mounting on a door casing, a guide tube extending across between opposite side walls of said box, a door engageable plunger projecting from one end of said tube, a plunger projecting spring engaged in the tube between said abutment and plunger, an electric switch within the box, said switch having a movable operating element, said plunger having a projecting portion operatively engaging said element, the tube having a slot through which said projecting portion protrudes, a locking member movably mounted on said tube and having a locking shoulder cooperative with said projecting portion of the plunger, the spring abutment being adjustable within the tube and having connection with said locking member for

effecting locking and unlocking adjustments of the same.

7. A door switch, comprising a box for mounting on a door casing, a guide tube extending across between opposite side walls of said box, a door engageable plunger projecting from one end of said tube, a spring abutment engaged in the opposite end of the tube, a plunger projecting spring engaged in the tube between said abutment and plunger, a switch within the box, said switch having a movable operating element and a cam projecting from the plunger into operative relation with said switch operating element, said tube having a guide slot receiving said cam.

8. A door switch, comprising a box for mounting on a door casing, a guide tube extending across between opposite side walls of said box, a door engageable plunger projecting from one end of said tube, a spring abutment engaged in the opposite end of the tube, a plunger projecting spring engaged in the tube between said abutment and plunger, a switch within the box, said switch having a movable operating element, a cam projecting from the plunger into operative relation with said switch operating element, said tube having a guide slot receiving said cam, said cam having an active switch throwing portion and an inactive switch holding portion.

9. A door switch, comprising a box for mounting on a door casing, a guide tube extending across between opposite side walls of said box, a door engageable plunger projecting from one end of said tube, a spring abutment engaged in the opposite end of the tube, a plunger projecting spring engaged in the tube between said abutment and plunger, a switch within the box, said switch having a movable operating element, a cam projecting from the plunger into operative relation with said switch operating element, said tube having a guide slot receiving said cam and a locking sleeve rotatably mounted on the tube and having a shoulder for holding engagement with the cam, said spring abutment being operatively connected with said sleeve and being rotatably adjustable within the tube for purposes of locking and unlocking the plunger and said tube having means for locking said abutment in the plunger locked position of the same.

10. A switch box, a guide tube extending across said switch box and opening through opposite side walls of the same, said tube having a longitudinal guide slot open at one of said side walls and said side wall having a notch in line with said guide slot, a plunger adapted to be entered through said end of the guide tube and having a projecting lug to pass through said notch into guided relation in said slot, a spring in the guide tube in back of said plunger, an abutment plunger entered in the guide tube in back of said spring, means for retaining said last mentioned plunger in position forming an abutment for the spring, the first mentioned plunger projecting from the opposite end of the tube for operation by a door or the like, and an electric switch within the box having an operating element engageable by said projection on the plunger.

11. A switch box, a guide tube extending across said switch box and opening through opposite side walls of the same, said tube having a longitudinal guide slot open at one of said side walls and said side wall having a notch in line with said guide slot, a plunger adapted to be entered through said end of the guide tube and having a projecting lug to pass through said notch into guided

relation in said slot, a spring in the guide tube in back of said plunger, an abutment plunger entered in the guide tube in back of said spring, means for retaining said last mentioned plunger in position forming an abutment for the spring, the first mentioned plunger projecting from the opposite end of the tube for operation by a door or the like, an electric switch within the box having an operating element engageable by said projection on the plunger, a sleeve rotatably engaged on the guide tube between said opposite side walls of the box, said sleeve being slotted for free passage of the plunger projection and having a locking shoulder shiftable by rotation of the sleeve into holding engagement with the projection, the spring abutment plunger having a key lug adapted to enter through the notch in the box wall into engagement in the slots in the fixed guide tube and rotatable locking sleeve and said guide tube having a keeper notch disposed at one side of the longitudinal slot therein for receiving and holding said key lug.

12. A switch box, a guide tube extending across said switch box and opening through opposite side walls of the same, said tube having a longitudinal guide slot open at one of said side walls and said side wall having a notch in line with said guide slot, a plunger adapted to be entered through said end of the guide tube and having a projecting lug to pass through said notch into guided relation in said slot, a spring in the guide tube in back of said plunger, an abutment plunger entered in the guide tube in back of said spring, means for retaining said last mentioned plunger in position forming an abutment for the spring, the first mentioned plunger projecting from the opposite end of the tube for operation by a door or the like, an electric switch within the box having an operating element engageable by said projection on the plunger, a sleeve rotatably engaged on the guide tube between said opposite side walls of the box, said sleeve being slotted for free passage of the plunger projection and having a locking shoulder shiftable by rotation of the sleeve into holding engagement with the projection, the spring abutment plunger having a key lug adapted to enter through the notch in the box wall into engagement in the slots in the fixed guide tube and rotatable locking sleeve, said guide tube having a keeper notch disposed at one side of the longitudinal slot therein for receiving and holding said key lug and a second keeper notch for receiving and holding said key lug in a partly turned position of the abutment plunger with the locking shoulder of the sleeve free of the plunger projection.

13. A door switch, comprising a switch box, plunger means having portions projecting from opposite sides of the box, one projecting portion for engagement and operation by a door and the other projecting portion being manually operable, switch mechanism in said box, a cam operable by the door actuated projecting portion of said plunger means and arranged to effect actuation of said switch mechanism and means operable by said manually actuated projecting portion for securing said plunger means and switch mechanism in predetermined condition, said means including a tubular member about said plunger means and said plunger means and tubular member being relatively rotatable in the retracted position of the plunger and having interlocking elements cooperable in such relative

rotation to effect the securing of the plunger means in retracted position.

14. A door switch, comprising a support, a door engageable plunger projecting from one side of said support, a cam connected with the inner end portion of said plunger, an abutment plunger projecting from the other side of the support and connected at its inner end with said cam, a spring for projecting the door engageable plunger, switch mechanism mounted on said support and operable by said cam and interlocking means on said abutment plunger and support for releasably retaining said door plunger and switch mechanism in predetermined relation, said means including a tubular member about said abutment plunger engageable in the retracted position of the connected plungers for securing the door engageable plunger in retracted position.

15. A door switch, comprising a support, a door engageable plunger projecting from one side of said support, a cam connected with the inner end portion of said plunger, an abutment plunger projecting from the other side of the support and connected at its inner end with said cam, a spring for projecting the door engageable plunger, switch mechanism mounted on said support and

operable by said cam and interlocking means on said abutment plunger and support for releasably retaining said door plunger and switch mechanism in predetermined relation, including cooperable elements engageable and disengageable by longitudinal and rotative movements of said abutment plunger on said support and means for limiting the extent of such engaging and disengaging movements of said abutment plunger.

- 10 16. A door switch comprising an enclosure for mounting on a door casing, a plunger projecting from said enclosure for actuation by a door in said door casing, an electric switch mounted in said enclosure and having a switch operating element, a cam operated by said plunger within the casing and engageable with said switch operating element for effecting actuation of the switch, a locking sleeve adjustable about said plunger within the enclosure and having means for interlocking engagement with the plunger in retracted position of the latter for effecting securing of said plunger in the retracted position, and externally accessible means for effecting securing and release adjustments of said sleeve.
